CLAIM

The ornamental design for a lid for cup, as shown and described.

DESCRIPTION

FIG. 1 is a front top perspective view of our lid for cup;
 FIG. 2 is a rear top perspective view of FIG. 1;
 FIG. 3 is a front view of FIG. 1;
 FIG. 4 is a rear view of FIG. 1;
 FIG. 5 is a top plan view of FIG. 1;
 FIG. 6 is a right-side view of FIG. 1;
 FIG. 7 is a front perspective view of FIG. 1;
 FIG. 8 is a rear perspective view of FIG. 1;
 FIG. 9 is a left side view of FIG. 1; and,
 FIG. 10 is a bottom plan view of FIG. 1.
 The broken lines and the areas within them depict portions
 of the lid for cup that form no part of the claimed design.

1 Claim, 5 Drawing Sheets
